(57) CLAIM

The ornamental design for a foldable box for boardgames, as shown and described.

DESCRIPTION

FIG. 1 is a perspective view of the present invention of foldable box for boardgames in the unfolded position; FIG. 2 is a top view of the foldable box for boardgames of FIG. 1;

FIG. 3 is a perspective view of the foldable box for boardgames of FIG. 1 with one half of the box folded;

FIG. 4 is a perspective view of the foldable box for boardgames of FIG. 1 with both halves of the box folded;

FIG. 5 is a top view of the foldable box for boardgames of FIG. 4;

FIG. 6 is a side view of the foldable box for boardgames of FIG. 4;

FIG. 7 is a perspective view of the foldable box for boardgames of FIG. 4 with the middle section of the box folded;

FIG. 8 is a top view of the foldable box for boardgames of FIG. 7;

FIG. 9 is a side view of the foldable box for boardgames of FIG. 7;

FIG. 10 is a bottom view of the foldable box for boardgames of FIG. 7;

FIG. 11 is a perspective view of the foldable box for boardgames of FIG. 1 with all the sections folded and the upper half in the open position;

FIG. 12 is a top view of the foldable box for boardgames of FIG. 11;

FIG. 13 is a side view of the foldable box for boardgames of FIG. 11;

FIG. 14 is a bottom view of the foldable box for boardgames of FIG. 11;

FIG. 15 is a perspective view of the foldable box for boardgames of FIG. 1 with all the sections folded and the upper half in the closed position with the bottom half;

FIG. 16 is a top view of the foldable box for boardgames of FIG. 15; and,

FIG. 17 is a side view of the smaller length side of foldable box for boardgames of FIG. 15.
